UNITED STATES PATENT OFFICE.

ARTHUR J. RICHARDS, OF JERSEY CITY, NEW JERSEY, AND FREDERICK J. SIEDENBURG, OF BROOKLYN, NEW YORK.

HAND TOOL.

Application filed December 18, 1923. Serial No. 681,405.

To all whom it may concern:

Be it known that we, ARTHUR J. RICHARDS and FREDERICK J. SIEDENBURG, both citizens of the United States, and residents, respectively, of Jersey City, in the county of Hudson and State of New Jersey, and of the city of New York, borough of Brooklyn, in the county of Kings and State of New York, have invented a new and Improved Hand Tool, of which the following is a full, clear, and exact description.

The present invention relates to new and useful improvements in devices for converting reciprocating motion into rotary motion, and while the mechanism is adapted to general uses, it is particularly adapted for use in connection with valve grinding tools and similar devices.

It is one of the primary objects of the present invention to provide a new and improved hand tool for grinding valves of internal combustion motors and the like.

It is a further object of the invention to provide means whereby a valve engaging tool may be given intermittent rotary motion in opposite directions in order to grind the valve to its seat.

It is a further object of the invention to construct the device in such a manner that the valve engaging tool may be maintained in engagement with the valve operated upon, with one hand and driven by the other hand of an operator.

It is a further object of the invention to construct the device in such a manner that the operating means of the valve engaging tool is adjustable relatively thereto.

With the above and other objects in view, reference is had to the accompanying drawings, in which—

Figure 1 is a perspective view of a tool constructed in accordance with the present invention showing a fragmentary section of an element having a valve seat and a valve mounted therein.

Fig. 2 is a horizontal sectional view of the device taken in a plane above the valve engaging tool operating means.

Fig. 3 is a vertical sectional view on the line 3—3 of Fig. 1.

Referring more particularly to the drawings, the reference numeral 5 designates an internal combustion engine cylinder or other member having a valve seat 6 and a

valve 7 mounted therein, such valve 7 having a kerf or other suitable recess 8 in its top face.

The tool comprises a U-frame 10, and the open side of the U-frame 10 is closed by a channel member 11 secured to the ends 60 of the legs of the U-frame by rivets, bolts or the like 12. The U-frame 10 is provided with an operating handle 13 secured to one of the legs thereof as at 14. Mounted in the U-frame there is a drum or pulley member 15, and such drum or pulley member is provided with a peripheral channel 16. Passing around the drum or pulley member 15, there is a cord 17, one end of which is attached, as at 18, to the U-frame, the other end being attached to a yoke 19 which straddles one of the legs of the U-frame 10 and is adjustable with relation thereto by means of a bolt or the like, 20. By this means the strain under which the cord 17 is placed may be adjusted in order to vary its frictional engagement with the drum or pulley member 15.

The peripheral channel of the drum or pulley member 15 is adapted to receive the U-frame at one point and the peripheral edge of the drum or pulley member 15 travels within the channel member 11, as more clearly shown in Fig. 3. By this construction the drum or pulley member 15 is maintained in position with the U-frame.

The drum or pulley member 15 is provided with a centrally disposed squared opening 21 and passing through said opening there is a squared shaft 22, the upper end of which is reduced as at 23 and provided with a loose hand wheel 24. Carried by the squared shaft 22 intermediate of its ends, there is a collar 25, which is adapted to be adjustably secured to the squared shaft 22 by means of a set screw or the like, 26. The lower end of the squared shaft 22 is provided with a bit 27 of a suitable shape to be received within the recess 8 on the upper face of the valve member 7.

From the foregoing it is apparent that when the bit 27 is engaged in the recess 8 of the valve member 7, if the U-frame be reciprocated, through the medium of the cord 17 which passes around the drum or pulley member 15, the squared shaft 22 will be intermittently rotated in opposite direc-

tions, and said intermittent rotary movement will be transmitted to the valve in order to grind the same to its seat 6.

By varying the position of the collar 25 on the squared shaft 22, the position of the U-frame relative to the ends of the squared shaft 22 may be adjusted.

It is apparent from the above that the present invention provides a new and improved hand tool especially adapted for grinding valves and similar work, and in which the valve is maintained in proper engagement with its seat during the grinding operation.

15. What is claimed is:

1. A device of the character described comprising a U-frame, a channel member closing the open side of said U-frame, a driving member mounted between the U-frame and the channel, a cord connected to the U-frame and passing around said driving member, and a shaft passing through the driving member and operably connected thereto.

2. A device of the character described comprising a U-frame, a channel member closing the open side of the U-frame with

its channel opening disposed inwardly thereof, a driving member mounted in the U-frame between the channel member and the U-frame, a shaft passing through the driving member and operably connected thereto, and a cord passing around said driving member, said cord having its ends attached to the U-frame whereby reciprocating motion of the U-frame will impart rotary motion to the driving member.

3. A tool of the character described comprising a U-frame having its open side closed by a channel member with its channel opening disposed inwardly of the U-frame, a driving member comprising a circular peripheral channel member mounted in the first-mentioned channel member and having a portion of the U-frame received in its own peripheral channel to provide for mounting the driving member between the U-frame and the first-mentioned channel member, and means carried by the U-frame for imparting intermittent rotary motion in opposite directions to the driving member.

AERTHUR J. RICHARDS.
FREDERICK J. SIEDENBURG.
